UNITED STATES PATENT OFFICE.

JOHN HERBERT VEASEY, OF JOHANNESBURG, TRANSVAAL, SOUTH AFRICA.

CLAMP.

Application filed June 5, 1924. Serial No. 718,159.

The present invention relates to fluid-actuated clamps. An object of the invention is to provide a simple and compact device adapted to effect simultaneously two clamping operations, such as clamping a rock drill to a saddle and clamping the saddle to a supporting arm.

In the accompanying drawings Fig. I is a vertical section of a rock drill clamp according to this invention.

Fig. II is a plan, sectioned on II-II in Fig. 1.

Figs. III and IV show detail modifications.

Fig. V is a vertical section of another form of clamp.

1 indicates an arm to which a rock drill is to be secured. The cradle of the rock drill is indicated by 2 and is provided with 20 the usual foot 3 having a conical upper surface 4 and a flat base 5.

For gripping the arm 1 there are provided the two jaws 6, 7 having arcuate inner surfaces to seat on the arm 1.

25 The foot 3 is seated in a head 8. Two removable jaw plates 9 are engaged in channels 10 formed in the head transversely to the axis of the foot 3. Said jaw plates have internal conical gripping surfaces 11 which, when the jaw plates are slid in place as shown, engage the conical surface 4 of the foot and retain the foot in the head. The jaw plates are retained in position by the pins 12 passed into place behind them. One 30 movable jaw plate only may be employed, the other being made integral with the head; but the use of two (or more) movable jaws has the advantage that a heavy body such as a rock drill can be dropped directly 35 into the position on the head in which it is to be clamped. A plunger jaw 13 extends through an opening 14 in the head coaxially with the foot 3 to engage the base 5 of the foot. The foot is secured by forcing said 40 plunger jaw 13 and the jaw surfaces 11 towards one another.

The jaw movement is derived from the pressure members 15, 16 which are forced apart by fluid pressure between them. Said 45 members have to be of considerable area to give the requisite clamping pressure with the fluid pressure ordinarily available, such as the pressure of the water or compressed air used in mines in connection with rock drilling. In order to provide the necessary area without excessive weight, said mem-

bers 15 and 16 are conveniently somewhat thin metal discs. A space or chamber 16^a between them is enclosed peripherally by an annular member which may be a loose ring 60 17, (Fig. I) having end flanges 18 for retaining it in assembly with the discs 15, 16. Said annular member may also be an annular flange 17^a fixed with respect to one of the discs say 15, as shown in Fig. III, 65 forming with said disc a cylinder in which the other disc 16 functions as a piston. Such a cylinder is preferably directed downwards when the rock drill is in its usual position above the arm 1, to avoid the collection of 70 dirt in it. In another modification, Fig. IV, both discs 15 and 16 are provided with overlapping flanges 17^b.

A short separating movement of the discs 15 and 16 being all that is necessary, the fluid for forcing them apart is conveniently retained in a flexible bag 19 which is enclosed and supported over substantially its whole area by the members 15, 16, 17. Said bag may be jointed with the fluid inlet 75 socket 20 by forming on it a tubular extension 21 which seats within said socket. Holes 22 formed in the latter permit the escape of any pressure fluid which may find its way between the outer surface of the extension and the socket, thus maintaining atmospheric pressure between the extension 21 and the inner wall of the socket whereby the higher pressure of the fluid within the extension holds the latter in fluid tight contact with the socket. Other means for retaining the fluid may however be used, such as the cup leathers 23 in the piston and cylinder construction of Fig. III.

The relative movement of the discs 15, 16 is transmitted to the opposite jaw members in any suitable manner. In the Fig. I construction the jaw 6 is seated on and preferably made integral with or fixed to, the disc 15. The plunger jaw 13 and the 100 jaw 7 are made in one piece; and the head 8 is moved relatively to them, from the disc 16, by pillars comprising bolts 24 and distance sleeves 25 which secure the head 8 and disc 16 rigidly together.

In the modified construction of Fig. V the fluid pressure container is interposed between the arm jaw 7 and the plunger jaw 13. The pillars 24, 25 connect the head 8 to a yoke 26 associated with the jaw 6.

For maintaining parallelism between the discs 15, 16 the pillars 24, 25 are utilized

as guides on which slide sleeves 27 rigidly fixed to the disc or discs to be guided. In the Fig. I construction as the pillars 24 are intended to be rigidly fixed to the disc 16, the disc 15 is provided with guide sleeves 27. In the Fig. V construction both discs

5 15 and 16 being movable relatively to the pillars 24, 25 are each provided with guide sleeves indicated by 27 and 27^a.

10 Compactness and strength is attained by arranging the pillars 24, 25 within the periphery of the discs 15, 16 and close to the jaws 6, 7. In both the Fig. I and Fig. V constructions the pillars extend at each end 15 beyond the jaws 6, 7; and long guiding surfaces substantially equal to the height of said jaws 6, 7, are thus available to prevent relative tilting of the discs 15, 16 as they are forced apart.

20 The jaw member 7, 13 may be retained from falling out of place when it is separated from the arm 1 by connecting it to the jaw 6 by loosely fitting dowels 28.

I claim—

25 1. In a clamp, clamping jaws, pressure members associated with the jaws, means between the pressure members to receive fluid pressure for relatively moving said jaws, pillars extending in the direction of movement and serving to transmit pressure to the jaws, said pillars being slideable through the pressure members, and sleeves rigidly connected to the pressure members slideable on said pillars for maintaining parallelism between the pressure members, said sleeves being slideable in opposite directions with respect to each other.

30 2. In a clamp, clamping jaws, pressure members having between them a space, means in the space adapted to receive fluid pressure for relatively moving said jaws, pillars positioned within the periphery of said pressure members and extending transversely to said members to transmit pressure

45 to the jaws, and sleeves slideable in opposite directions on said pillars and connected to said members for maintaining parallelism between the pressure members, and means slideable on said members to enclose said space.

50 3. In a clamp, a pair of opposed jaws, pressure members having between them a space, flexible means in the space to receive fluid pressure for relatively moving said jaws, one of said pressure members acting directly on a jaw, pillars transmitting pressure to the other jaw and extending past said pair of jaws, sleeves slideable in opposite directions on said pillars and connected to said members for maintaining parallelism between the pressure members, and means slideable on the periphery of said members for enclosing said space.

55 4. In a clamp, a pair of opposed arcuate jaws, a head movable relatively to the jaws, a pair of conical jaws slideable transversely in said head, pins for retaining the jaws in the head, a plunger working through the head and opposing said conical jaw means and forming therewith a second pair of jaws, and fluid actuated means arranged for forcing the members of said several pairs towards one another.

60 5. In a clamp, a head, conical jaw means removably held therein, the head being adapted to receive a conical member when the jaw means are removed, and said conical jaw means when in position engaging the conical face of the member, pins extending through the head to form an abutment for the jaws to retain said member, a plunger working through the head to engage the base of the conical member and means to force said plunger towards the conical jaw means.

65 85 In testimony whereof I affix my signature.

JOHN HERBERT VEASEY.
